UNITED STATES PATENT OFFICE.

CHARLES E. JONES, OF CHICAGO, ILLINOIS, ASSIGNOR TO METAL ARTS AND CRAFTS CO., OF CHICAGO, ILLINOIS, A CORPORATION OF ILLINOIS.

DESIGN FOR AN ARM FOR SHOWER-PANS OR LIGHT-FIXTURES.

45,879.

Specification for Design.

Patented June 2, 1914.

Application filed March 28, 1914. Serial No. 828,089. Term of patent 3½ years.

To all whom it may concern:

Be it known that I, CHARLES E. JONES, a citizen of the United States, residing at Chicago, in the county of Cook and State of Illinois, have invented a new, original, and ornamental Design for Arms for Shower-Pans or Light-Fixtures, of which the following is a specification, reference being had to the accompanying drawing, forming a part thereof.

Figure 1 is a side elevation of my improved design. Fig. 2 is a front elevation of the same.

I claim:

The ornamental design for an arm for shower pans or light fixtures as shown.

CHARLES E. JONES.
